UNITED STATES PATENT OFFICE

MARSHALL H. PAGE, OF NEW YORK, N. Y., ASSIGNOR, BY DIRECT AND MESNE ASSIGNMENTS, TO LINE-O-GRAPH COMPANY, OF KANSAS CITY, MISSOURI, A CORPORATION OF MISSOURI

ADVERTISING DEVICE

REISSUED

Application filed February 9, 1929. Serial No. 338,698.

The object of my invention is to provide cheap, durable, reliable and effective advertising signs, which will perform the double function of constantly changing the reading matter of one sign and making the light appear and disappear on another sign adjacent to the first, so that attention will be attracted and interest aroused at all times when the device is in operation. This object is accomplished by my invention, one embodiment of which is hereinafter more particularly set forth.

For a more detailed description of my invention, reference is to be had to the accompanying drawings, forming a part hereof, in which

Figure 1 is a longitudinal section of one embodiment of my invention, the section being taken on the line 1—1 of Figure 2, looking in the direction of the arrows.

Figure 2 is a sectional view, taken on the line 2—2 of Figure 1, looking in the direction of the arrows.

Figure 3 shows a portion of the mechanism for changing the reading of a sign.

Figure 4 is a front elevation of the device showing the parts in which signs appear, or pictures or other advertisement, with changing effects, as above noted.

Figures 5 and 6 are side elevations showing how its front is attached or removed from the body of the apparatus.

Figure 7 shows a slide which may be inserted in the front.

Figures 8 and 9 are sectional views of the rotor shown in Figure 3.

Throughout the various views of the drawings, similar reference characters designate similar parts.

My improved advertising device 1 has a housing 2 closed by a removable front 3 and provided with two chambers 4 and 5 in which are placed electric lights 6 and 7 which are mounted and connected in the conventional way. In the preferred embodiment of my invention, a light 7 is employed which is of the intermittent type, that is as soon as it illuminates it goes out. The chambers 4 and 5 are open at the front and adjacent to a removable sign 8, shown in Figure 7, which

has a frame 9 with two openings covered by transparencies 10 and 11, the transparency 10 being preferably made of colored, translucent paper and carrying no lettering or figures or pictures. The sign 11 is also translucent and carries any desired ornament, letters, etc. Care is taken so as to make the chambers 5 and 4 so that light will not leak from one to the other.

The floor 12 of the chamber 4 is secured to the frame 2, in any suitable manner, and in front of the lamp 6, or at any other convenient location, it carries a spindle or pivot 13 which is fixed therein in any desired way and preferably held true by a bracket 14. The upper end of the spindle 13 is pointed and is adapted to engage a glass center 15 from which radiate the vanes 16, in the conventional manner, and the outer ends of these vanes are secured to a transparency 17 which carries any desired lettering, or other sign, in register with the window 10. As heat rises from the lamp 6 it causes the vanes 16 to shift so that the rotor 18, of which they form a part, revolves with light passing through the member 17 and letters, or other features on this part 17, are projected on the window 10 and constantly pass thereover, so that it is easy to read a sign on this rotor. Immediately below is another sign on the window 11 which is illuminated momentarily by the lamp 7.

The casing 2 is closed at its top by a suitable hinged cover 19 which may be made in any conventional way, but is preferably so made that air may enter through the openings 20 at the bottom of the casing 2, pass through suitable openings 21 in the floor 12 and about the lamp 6 and up through the vanes 16 to an opening 23 in the cover 19 and thence out at the rear. The front 3 may be secured to the casing 2 in any suitable way as by means of pins 24 which extend inwardly from flanges 25 which form a part of the front and into bayonet sockets 26 in the casing 2.

In view of the foregoing, the operation of my improved advertising device will be readily understood. Assuming that the lights 6 and 7 are illuminated and function, as above

described, air enters through the openings 20 and 21, passes by the light 6, where it is heated, and thence passes upwardly to the vanes 16 which drive the rotor 18 so that the rotor revolves in a proper direction, and thence outwardly through the opening 23 in the top 19. The rotation of the rotor 18 causes the same to function as a moving picture device so that a picture, or letters, or numerals, or what not, may be projected on the window 10, as above set forth, whereby a sign with constantly changing characteristics appears on this window. At the lower window 11 is another sign which may be continuously illuminated, but is preferably intermittently illuminated, as above set forth. These signs are reliable and will function until a light burns out, at which time it must be replaced for further operation of the device.

20 While I have shown and described one embodiment of my invention, it is obvious that it is not restricted thereto, but that it is broad enough to cover all structures that come within the scope of the annexed claim.

25 Having thus described my invention, what I claim is:

In an advertising device, two compartments, one having a horizontal portion forming 30 a floor, said horizontal portion being secured to a vertical portion forming a wall, flaring upper and lower parts integral with said wall forming one of said compartments, a rotatable sign with means for driving the same mounted upon said floor projecting over 35 said flaring parts, a window in front of said sign, means for illuminating said sign so that the movable sign may be read through said window, another sign in front of said flaring parts and means enclosed in said last named 40 compartment for illuminating said sign in front of the flaring parts, the two illuminating means being separated by the upper flaring part and a part of said vertical wall thereby forming a light-proof partition.

45 In testimony whereof, I have hereunto set my hand this 7th day of February, 1929.

MARSHALL H. PAGE.
